United States Patent Office

Des. 192,915
Patented May 29, 1962

192,915

GIRDLE

Anna Y. Bayer, 90 Whitney Ridge Terrace,
North Haven, Conn.

Filed Jan. 23, 1961, Ser. No. 63,658

Term of patent 14 years

(Cl. D20—2)

FIG. 2

FIG. 1

FIG. 3.

The essential features of my design are shown in full lines on the drawing.

I claim:

The ornamental design for a girdle, as shown and described.
